RECEPTACLE AND METHOD OF MAKING
THE SAME

Henry Kielberg, Martins Ferry, Ohio, and Thomas P. Parker, Wheeling, W. Va., assignors to Wheeling Steel Corporation, Wheeling, W. Va., a corporation of Delaware

Application July 14, 1932. Serial No. 622,420

4 Claims. (Cl. 220—19)

The present invention relates broadly to the art of special receptacles, and more particularly to wire receptacles of the type adapted to be utilized for either the retention or burning of refuse materials.

It is customary in the art to which the present invention relates to provide receptacles, usually composed of substantially vertically and substantially horizontally disposed members secured one to the other in suitable manner and of a generally tapered contour for the reception of waste papers and the like to be burned. It has heretofore been customary to fabricate receptacles of this nature on special machines adapted to provide a body blank of the necessary contour to effect a finished receptacle in the form of a truncated cone. Such machines are of extremely complicated nature and while capable of providing a finished receptacle which is perfectly acceptable to the trade, are open to objection from the standpoint of initial expense and the cost of upkeep.

It is one of the objects of the present invention to provide a receptacle of the general characteristics hereinbefore described by fabricating the same from a blank in the form of a body comprising parallelly disposed vertically extending members and parallelly disposed horizontally extending members and thereafter so deforming the horizontally extending members as to give to the initial substantially rectangular body blank the desired characteristics for forming a tapered body. This enables the members of which the receptacle is fabricated to be secured together by standard mechanisms, such for example as a fence machine, and thereby increases the potential output and decreases the cost of production.

In the accompanying drawings we have shown for purposes of illustration only, a receptacle in accordance with the present invention, together with a preferred method of making the same. In the drawings—

Figure 1 is a side elevational view of a finished receptacle in accordance with my invention;

Figure 2 is a transverse sectional view on the line II—II of Figure 1;

Figure 3 is a transverse sectional view on the line III—III of Figure 1;

Figure 4 is a transverse sectional view on the line IV—IV of Figure 1;

Figure 5 is a transverse sectional view on the line V—V of Figure 1;

Figure 6 is a detail view, on an enlarged scale, of a portion of the side wall and bottom;

Figure 7 is a side elevational view of a body

blank from which the main body of the receptacle is formed;

Figure 8 is a detail view, on enlarged scale, illustrating the manner in which the horizontally disposed members are progressively increasingly deformed in accordance with the invention; and

Figure 9 is a detail sectional view on an enlarged scale along the line IX—IX of Figure 1, looking in the direction of the arrows.

In accordance with the present invention, I fabricate, on any suitable machine, a body forming portion 2 as indicated in Figure 7, comprising substantially horizontally disposed members 3, 4, 5, 6 and 7 arranged in substantially parallel relationship and vertically extending members 8 also in substantially parallel relationship. The body blank is conveniently formed by welding the horizontally and vertically extending members one to the other at each of their points of intersection 9 and by wrapping the opposite ends 10 of the vertically extending members around the top and bottom horizontally extending members.

The body blank having been thus fabricated, it is subjected to a deforming operation, which may be conveniently accomplished by corrugated rollers, not shown, by hand, or in any other desired manner, of such nature that the substantially horizontally extending member 4 has slight inwardly extending offsets 11 formed therein intermediate adjacent vertically extending members 8. The horizontally extending member 5 has similar inwardly extending offsets 12, as shown in Figure 3, which offsets, however, are slightly greater than the offsets in the member 4. In like manner the member 6, as shown in Figure 4 is formed with sharper offsets 14 while the bottom member 7 has offsets 15 of the greatest amount. In Figure 8 there is illustrated comparatively the construction just described.

By reference to this figure, it will be noted that the top member 3 is not deformed, but that the offsets 11, 12, 14 and 15 in the members 4, 5, 6 and 7 are of progressively increasing extent. The amount by which the offsets in the successive horizontally disposed members exceeds the offset in the next adjacent member therebelow is controlled by the amount of taper which it is desired to impart to the finished receptacle illustrated in Figure 1, it being apparent that as the offsets are progressively increased in the successive horizontally extending members from the top to the bottom thereof, the average diameter or length of the horizontally extending members is correspondingly shortened.

The deforming operation just described may

take place either with the body blank in the form in which it is generally illustrated in Figure 7, or after the projecting end portions of the horizontally extending members have been secured together in some suitable manner, as by welding. In one case the operation will be effective for shortening the length of the horizontally extending members, while in the other case it will be effective for progressively decreasing the average diameters of the circumferentially extending members. In either case the vertically extending members 8, which were previously disposed in substantially parallelly extending relationship will be drawn into a gradually converging relationship from the upper portion of the receptacle downwardly. This relationship is clearly illustrated in Figure 1.

The foregoing operations having been performed, a bottom 16 of suitable construction, and herein illustrated as comprising a wire grille of circular contour may be placed within the receptacle in such manner that it rests on the inwardly directed offsets 14 of the circumferentially extending member 6. Having been located in the manner described, it may be secured in position in any desired manner, preferably by welding directly to some or all of the offsets 14. Thereafter, a suitable cover 17, preferably similar to the bottom 16 but of slightly greater diameter 30 may be placed over the receptacle and pivotally secured in position as by a ring 18 extending around the circumferential band of the cover and the top band 3 of the body. This relationship is illustrated in detail in Figure 9.

35 The receptacle as thus constructed is in the form of a truncated cone with the turned ends 10 and the bottom band 7 constituting a base therefor. The space between the bottom band 7 and the next adjacent band 6 which supports the bottom 16 insures ample room for the access of combustion air below the bottom 16 which, as will be apparent, serves as a grate, while the remaining portion of the receptacle is available for receiving the matter to be burned.

40 The present invention provides both an improved article of manufacture and an improved method of making the same. The inward bending or deforming operation before described provides pockets in each of the circumferentially extending bands which are more effective for holding the vertically disposed members against displacement. Also, the offsets 14 in the circumferentially extending band 6 provide a convenient means for supporting a bottom grille or grate in 45 position.

Further advantages are inherent in the method

which enables a receptacle of the special characteristics referred to to be formed on a fabricating machine of the type utilized for the making of fences without special regard to the tapered contour desired in the finished product, coupled with the deforming step by means of which the tapered characteristics are imparted.

80 While we have herein illustrated and described the preferred method and article in accordance with our invention, it will be understood that changes in the construction and relationship of the parts as well as in the contour or cross section of the parts may be made without departing either from the spirit of our invention or the 85 scope of our broader claims.

90 We claim:

1. As an article of manufacture, a receptacle having the shape generally of a truncated cone, comprising substantially vertically disposed members in downwardly converging relationship, circumferentially disposed members secured thereto, and inwardly extending offsets in the circumferential members, said offsets being of increasing extent from the top of the receptacle 95 downwardly.

2. As an article of manufacture, a receptacle comprising substantially vertically disposed members in downwardly converging relationship, circumferentially disposed members secured thereto, and inwardly extending offsets in the 105 circumferential members, said offsets being of increasing extent from the top of the receptacle downwardly.

3. As an article of manufacture, a receptacle comprising substantially vertically disposed members in downwardly converging relationship, circumferentially disposed members secured thereto, inwardly extending offsets in the circumferential members, said offsets being of increasing extent from the top of the receptacle 110 downwardly, and a bottom resting on the inwardly extending offsets of one of the circumferentially disposed members.

4. As an article of manufacture, a receptacle comprising substantially vertically disposed members in downwardly converging relationship, circumferentially disposed members secured thereto, inwardly extending offsets in the circumferential members, said offsets being of increasing extent from the top of the receptacle 115 downwardly, and a bottom resting on the inwardly extending offsets of one of the circumferentially disposed members and secured thereto.

120 HENRY KIELBERG.
THOMAS P. PARKER.
